UNITED STATES PATENT OFFICE

2,352,274

SEWING MACHINE

Bernard T. Leveque, Wenham, Mass., assignor to
United Shoe Machinery Corporation, Flemington, N. J., a corporation of New Jersey

Application June 17, 1941, Serial No. 398,368

35 Claims. (Cl. 112—34)

The present invention relates to machines for sewing shoes or other articles composed of stiff, heavy materials, and is hereinafter illustrated as embodied in a shoe sewing machine of the straight hook needle type disclosed in U. S. Letters Patent to Merrick Nos. 490,854 to 490,857 inclusive, dated January 31, 1893.

The machine of these patents is a chainstitch sewing machine having an awl arranged to penetrate the work from above and form a perforation for a straight needle entering the perforation from beneath the work as the awl withdraws. The needle, after entering the awl perforation, carries the work out of line with the awl the length of a stitch preparatory to the formation of a new awl perforation, thus imparting a feeding movement to the work. In the form described in the patents, that machine is effective even in comparison with more modern machines at the present date for sewing a satisfactory seam when carefully and expertly adjusted, but mechanical limitations to which the patented machine is subject, render its use difficult, due to frequent delays required in maintaining the condition of proper adjustment, particularly when being operated at high speeds. The needle and awl of that machine are driven from a main sewing shaft through simple and mechanically advantageous mechanisms including crank actuated connections, the needle being actuated when entering the work to follow the awl closely, thus insuring proper alignment of the needle with the awl perforation. With crank actuated needle and awl mechanisms arranged in this way, the speed and accuracy of sewing operations are sufficient for many present day sewing requirements, but since both the needle and awl must be free of the work when the work is withdrawn from the machine at the end of a seam or when new work is being substituted, it frequently is difficult with thick heavy work to make proper sewing adjustments in the patented machine which will not work to a disadvantage so far as easy removal or substitution of the work in the machine is concerned.

The objects of the present invention are to provide a shoe sewing machine of simplified construction and improved mode of operation for doing the same type of work heretofore performed with the machine of the Merrick patents referred to above and which will more easily be adjusted both for effective high speed sewing conditions, as well as for convenient removal of the work at the end of a seam.

Other objects are to provide a machine for this type of work in which difficulties inherent in the patented machine including those difficulties above enumerated are avoided and which may be operated successfully at sewing speeds higher than heretofore considered possible with the patented machine, without danger of sacrifice in durabil-

ity of the machine, in quality of work performed or in amount of skill or effort required on the part of the operator.

A still further object is to provide a novel and improved driving and stopping mechanism for sewing machines, the use of which renders possible simple and effective actuating mechanisms for the needle and awl, which mechanisms heretofore have caused a machine so equipped to be capable of competing with other machines only under a definite handicap so far as removal or substitution of work is concerned.

With these and other objects in view, a feature of the present invention contemplates the provision in a shoe sewing machine having mechanisms driven from a sewing shaft for actuating the needle and awl comprising an element movable to disconnect either the needle or awl from the sewing shaft during the final sewing cycle of a machine to cause the disconnected instrument to come to rest out of engagement with the work as the other instrument continues its movements to complete the sewing cycle. This feature enables the needle to be withdrawn from engagement with the work while the awl remains stationary in its stopping position also out of engagement with the work. Disconnection of the awl from the sewing shaft is particularly advantageous in a sewing machine in which both the needle and awl are driven from crank actuated mechanisms and follow each other closely during each sewing cycle because the needle and awl mechanisms may, as a result, be adjusted for sewing without changing the distance between the needle and awl when the machine is brought to rest. Thus, when unusually thick work is being operated upon, no difficulty is encountered during sewing due to the necessity of increasing the distance between the needle and awl required for removal of the work. Preferably, means are provided for bringing the needle to rest out of engagement with the work after the awl has reached its stopping position. In this form of the invention, the needle mechanism also is provided with a disconnecting element and control of both needle and awl disconnecting elements is effected by members driven from the sewing shaft.

This feature of the invention also includes master timing means for causing actuation of the disconnecting elements in the proper sequence during the final sewing cycle, the control members in the illustrated construction acting in substantially the same timed relation when the sewing operations are being started as when stopped. To insure that the needle and awl are retained in stopping positions, according to this feature of the invention, the needle and awl are locked after being disconnected from the sewing shaft at the end of a seam, and are un-

locked when the machine is started. Although the present embodiment of the invention comprises elements for disconnecting the needle and awl only, certain stitch forming devices, other than the needle and awl, which operate in timed relationship with each other, may be disconnected to advantage and locked in their respective stopping positions in cases where it is desirable to move them out of sewing relationship during stopping.

The machine hereinafter described is also provided with a novel thread cutter and simplified and improved means for controlling the thread and also an improved form of presser foot lock. In addition to these features, the invention is embodied in certain constructions, combinations and arrangements of parts hereinafter described and claimed, the advantages of which will be apparent to those skilled in the art from the following description.

Referring to the drawings, Fig. 1 is a view in side elevation, looking from the right of the machine, embodying the features of the present invention; Fig. 2 is a view in front elevation of the machine illustrated in Fig. 1 on a slightly enlarged scale; Fig. 3 is a cross-sectional view on a further enlarged scale, broken out to reduce the lengthwise dimension, and taken along a horizontal plane indicated by the line 3—3 of Fig. 1; Fig. 4 is a view in front elevation, partly broken away and in section of the machine illustrated in Fig. 1; Fig. 5 is a view in front elevation of the upper portion of the machine, a front cover having been broken away to illustrate the awl and presser foot lock actuating mechanism, with the parts indicated in positions assumed when the machine is brought to rest and the presser foot lifted; Fig. 6 is a view in front elevation of the presser foot lock actuating mechanism taken during sewing operations while the presser foot is locked in engagement with the work; Fig. 7 is a sectional view taken along the line 7—7 of Fig. 6; Fig. 8 is a side sectional view taken along the line 8—8 of Fig. 5; Fig. 9 is a sectional plan view of the looper and tension devices taken along the line 9—9 of Fig. 8; Fig. 10 is a view in vertical section taken through the main sewing shaft of the machine at its rearward end, illustrating a portion of the driving and stopping mechanism with the parts in stopped positions; Fig. 11 is a view in front elevation of the lower portion of the machine, a cover plate having been broken away to illustrate the needle cast-off and thread cutter actuating mechanisms; Fig. 12 is a sectional view taken along the line 12—12 in Fig. 11; Fig. 13 is a sectional plan view taken along the line 13—13 of Fig. 12, showing the thread cutter after being actuated to sever the thread; Fig. 14 is another sectional plan view taken along the line 14—14 of Fig. 12; Fig. 15 is a view in front elevation of the stitch forming devices illustrating the positions assumed just before the awl enters the work to form a perforation for a new stitch; Fig. 16 is a view of the stitch forming devices just after the awl has penetrated the work and the needle has withdrawn; Fig. 17 is a detail view on an enlarged scale of the needle cast-off illustrating the positions assumed with relation to the work, as indicated in Fig. 15; Fig. 18 is a similar view corresponding to the positions of Fig. 16; Fig. 19 is a view in front elevation of the stitch forming devices showing the needle as it begins to enter the work; Fig. 20 is a view of the same parts taken during work feeding movement of the

needle; Fig. 21 is a detail plan view indicating the manner of looping the needle; Fig. 22 is a view in front elevation of the parts illustrated in Fig. 21; Fig. 23 is a detail view of the discon-
5 nectible connections in the awl actuating mechanism taken during sewing operations; Fig. 24 is a detail view in front elevation of the discon-
nectible connections for the needle actuating mechanism taken during sewing operations; Fig. 25 is a detail view of the awl actuating mechanism taken just after the connections are dis-
10 connected in stopping; Fig. 26 is a corresponding view of the awl actuating mechanism illustrating the positions of the parts during their continued
15 movements; Fig. 27 is a detail view of the master timing disk and its follower, showing an intermediate position while passing through the slot in the disk; Fig. 28 is a detail view of the awl actuating mechanism illustrating the positions of the
20 parts upon slight further movements of the sewing shaft from the position of Fig. 25; Fig. 29 is a detail view illustrating the corresponding positions of the needle actuating mechanism; Fig. 30 is a detail view of the awl actuating mecha-
25 nism taken just before the presser foot is lifted from the work; Fig. 31 is a detail view of the needle actuating mechanism corresponding to the position of the awl actuating mechanism illus-
30 trated in Fig. 30 and showing the position of the parts just after the needle actuating connections are disconnected; Fig. 32 is a detail view of the followers for the needle control member, together with their control cams, illustrating the positions as the machine is being brought to rest; Fig. 33
35 is a similar view of the needle control followers and cams as the machine is being started; Fig. 34 is a detail view of the awl actuating mechanism illustrating the position of the parts after the presser foot is lifted from engagement with the work; Fig. 35 is a corresponding detail view of the needle actuating mechanism; Fig. 36 is a detail view of the awl actuating mechanism illustrating the positions of the parts as the machine is being started in operation; Fig. 37 is a corre-
40 sponding detail view of the needle actuating mechanism illustrating how the connections remain disconnected until after the awl has penetrated the work; Fig. 38 is a detail view of the followers for the awl control member, together with their control cams illustrating the relative positions as the machine is being brought to rest; and Fig. 39 is a similar view of the awl control followers and cams illustrating their relative positions while starting sewing operations.

55 The sewing machine illustrated in the drawings is a chainstitch straight hook needle machine having an awl operating from above and the needle from below the work. A work feeding movement is imparted to the needle while engaging the work to advance the work a stitch length. The stitch forming devices of the machine are driven from a main sewing shaft through cranks, pitmen and suitable connections between the stitch forming devices and the sewing shaft, as in the machine of the Merrick pat-
60 ents above identified. To facilitate lubricating the machine, the operating and driving mechanisms are entirely enclosed by a tight hollow sup-
65 porting frame 1 having an overhanging arm, within which frame are oiling means including an oil pressure pump and spray and drip delivery jets (not shown).

70 In the illustrated machine, the straight hook needle is shown at 2 operating from below a for-
75 wardly projecting arm of a work support 4, and an

awl at 6 operating from above the work support and at the same side of the work support with a presser foot 8 movable towards and from the work support to clamp the work adjacent the points of needle and awl operation. Other stitch forming devices including a looper 10, a cast-off 12 and a sewing thread tension wheel 14, all operate in a manner similar, except as hereinafter described, to the corresponding devices in the machine of the patents. The awl is actuated by a crank 16 on a main sewing shaft 18 and the needle from a crank 20 on an auxiliary shaft 22 driven from the main sewing shaft through a bevel gear train including gears 24, 26, a vertical shaft 28 and gears 30, 32, all of which gears have the same number of teeth.

As in the above patents, the awl in the illustrated machine first penetrates the work in each sewing cycle and the needle follows the awl closely as the awl is being retracted from the work in order to insure that the needle will enter the perforation formed by the awl (see Fig. 19). To obtain this result with simple crank actuated mechanisms, as disclosed in the patents, the needle and awl driving cranks are arranged on the sewing shaft 18 and the auxiliary shaft 22 with an angular separation of approximately 180°. In order that the work operated upon may be removed readily in any sewing cycle in which the stitch forming devices are brought to rest and to provide space for looping the needle, it is sometimes necessary to depart slightly from the 180° angular separation between the needle and awl cranks in favor of a greater spacing between the needle and the awl while the needle engages the work and the awl crank is arranged to provide a longer stroke than the needle crank. By so doing, after the thread has been disengaged from the needle at the end of a seam, and the presser foot raised, the work may be removed without obstruction. Even with such provision for removing and replacing the work, when thick work such as is met in heavy shoe soles is being operated upon, it is necessary to adjust the positions of the needle and awl in their respective holders as far apart as possible consistent with practical sewing. However, to cause the needle to be projected sufficiently above the upper surface of the work and the looper to lay the thread with certainty in the hook of the needle, under these conditions, the looper also must be adjusted to carry the thread close to the upper surface of the work and adjustments in others of the stitch forming devices are necessary. When so adjusted, the machine is capable of operating successfully on thick work but not on thin work because the needle does not follow the awl sufficiently closely and by reason of other inaccuracies in timing. Under certain circumstances, particularly when the operating parts of the machine become worn, proper adjustment of the machine for different thicknesses of work becomes a practical impossibility and even under the best circumstances, proper adjustments when the thickness of the work is changed frequently result in loss of time and require special skill and ability on the part of the operator.

The machine of the present invention is capable of being so adjusted that it will operate upon a wide range of work thicknesses without any adjustment and when the thickness or quality of the work does require adjustments to be made, they may be completed with relatively few simple changes and without requiring general realignment of the operating parts and stitch form-

ing devices. As a result, operators of much less skill and experience may be employed than with the machine of the patent.

To enable the machine to sew relatively thick work without increasing the spacing between the needle and awl so that the work may be removed or replaced easily, the awl actuating mechanism has a train of connections between the crank 16 and the awl including an element movable to disconnect the awl from the sewing shaft during the last sewing cycle of the machine so that the needle may continue its movement and complete the stitch being formed and separate from the awl sufficiently to remove the work. The awl is brought to rest in a position at the end of its stroke most remote from the work and the needle continues its stitch forming movements until it, in turn, withdraws from the work.

In order to insure that the needle remains in this position as the machine is brought to rest, the needle driving mechanism also is provided with a train of connections having a disconnecting element acting after the needle has reached its stopping position. By arranging the needle and awl driving mechanisms in this way, the amount of angular separation between the needle and awl driving cranks is no longer a factor which determines the separation of the needle and awl in stopping and consequently, no adjustments are necessary for sewing relatively thick work.

The awl actuating mechanism comprises the pitman 34 (see Figs. 5 and 8), one end of which engages the crank 16, a driving lever 36 fulcrumed on a bolt 38 secured in the machine frame to which lever the pitman 34 is connected, and an awl lever 40 also fulcrumed on the stud 38 and connected through a link 42 to a reciprocating awl bar 44. During sewing operations, the driving lever 36 is connected with the awl lever 40 and during the last sewing cycle of the machine, the levers are disconnected, the awl lever being locked in position with the awl bar 44 at the highest point in its reciprocating travel. To connect and disconnect the levers 36 and 40, a latch link 46 is mounted to swing on a pin 48 secured in the end of the lever 40 and arranged with its hooked portion to be engaged with or disengaged from a pin 50 secured in the end of the lever 36. When the levers 36 and 40 are brought into alignment with each other (see Fig. 23), stop lugs 52, 54 on the respective levers hold the levers from relative movement in one direction and the latch link 46 engaging the pin 50 holds the levers from relative movement in the opposite direction. This is the condition for sewing operations and as a result, the movements imparted by the crank 16 are transmitted into reciprocating movements of the awl supporting bar 44. To keep the latch link 46 in engagement with the pin 50, there is coiled about the pin 48 a spring 56 (see Fig. 8), having one end inserted in a perforation of an enlarged head on the pin and the other end in a similar perforation in the side of the latch link. At the end of the sewing operations, the latch link is disengaged from the pin 50 and a slotted end of a locking arm 58 is brought into surrounding relationship with the pin 48 to lock the awl actuating lever 40 in stopped position (see Fig. 25). To disengage the latch link 46 from the pin 50 on the lever 36, the locking arm 58 carries a roll 60 operating on a side surface of the latch link when the locking arm is moved around the pin 48.

To actuate the locking arm 58, the present

machine is provided with driving and stopping mechanisms having a latch controller member, as in the machine of present inventor's U. S. Letters Patent No. 2,144,766 of January 24, 1939, and No. 2,283,073, of May 12, 1942, comprising a shaft 62 to which the locking arm 58 is secured, a stop arm 64 and a start arm 66 also secured to the control shaft 62. The stop and start control arms 64, 66 have cam rolls operated at certain times by stop and start cams 68 and 70 rotating with, but slideable lengthwise of, the sewing shaft 18. When the stop cam is brought into alignment with the roll on the arm 64, as in Fig. 38, the awl is disconnected and when the start cam is brought into alignment with the roll on the arm 66, as in Fig. 39, the awl is again connected with the sewing shaft.

The needle actuating mechanism, best shown in Figs. 3, 11 and 12, is generally similar to the awl actuating mechanism. On the needle actuating crank 20 is a stud surrounded by one end of a pitman 72, the other end of which is connected by a driving lever 74 fulcrumed on a bolt 76 in the machine frame. The bolt 76 also supports a needle actuating lever 78 connected through a link 80 to the lower end of a reciprocating needle bar 82. During sewing operations, the needle actuating lever 78 and the lever 74 move together as a unit, being connected by a latch link 84 arranged to swing on a pin 86 secured in the end of the needle actuating lever 78 towards and from a pin 88 at the end of the lever 74. To keep the hook portion of the latch link in engagement with the pin 88, the pin 86 is surrounded by a coil spring 90, one end of which is inserted in a perforation in the enlarged head of the pin 88 and the other end of which is inserted in a perforation in the side of the latch link.

The needle actuating latch link 84 is moved out of engagement with the pin 88 at the end of a seam by a locking arm 92 having its end suitably slotted to surround the pin 86 and provided with a roll 94 acting on the side of the latch link 84 to disengage it from the pin 88. The locking arm 92 is secured to one end of a shaft 96 forming together with stop and start arms 98 and 100, a controller member for the needle actuating mechanism. The stop and start arms are made fast in spaced positions along the shaft 96 and are provided with cam rolls cooperating with stop and start cams 102 and 104 rotating with, but slideable lengthwise of, the shaft 22. When the stop cam 102 is brought into alignment with the roll on the stop arm 98, as in Fig. 32, the needle is disconnected, and when the start cam 104 is brought into alignment with the roll on the arm 100, the needle is again connected with the sewing shaft.

To hold the needle controller member in actuated position, a toggle spring 105 (see Fig. 3), is stretched between a pin on the stop arm 98 and passes across the end of control shaft 96 to an eye bolt 106 secured in the frame of the machine. The hub of arm 98 also has an open slot into which projects the end of a limit pin 107 secured in the machine frame to prevent movement of the controller member beyond the position to which it is actuated by the control cams.

As has been stated, master timing means is provided to prevent movement of the stop and start cams along the sewing shafts except at one particular position of the sewing shaft so that the needle and awl controller members will

thereafter be actuated in a predetermined sequence to connect the needle with its actuating mechanism after the awl is connected or to disconnect the needle and awl in the same order. 5 Possible breakage also is avoided by the timing means by permitting actuation of the stop and start cams only when the low portions of the cams are opposite the rolls.

The timing means consists of a slotted disk 108 secured to the main sewing shaft 18 of the machine. Cooperating with the slotted disk 108 is a timing arm on a lever 109 having a roll 110 arranged to pass through the slot in the disk 108 when the slot is located opposite the roll and to be held from movement by the disk at other times. The lever 109 has an elongated hub rotatable on a shaft 112 which forms a portion of the treadle connections for actuating the control cams so that movements of the cams are prevented except when the timing disk and sewing shaft are in predetermined positions. The angular location of the slot in the timing disk is so adjusted that the treadle connections may be actuated at a time suitable to cause the awl actuating mechanism to become operative before the needle actuating mechanism is operative either in starting or stopping the machine.

The treadle actuated connections include a vertical treadle rod 114, a spring 116 (see Figs. 2 and 11), for raising the rod when released by the operator, an arm 118 secured to one end of a rock shaft 118 (Fig. 10) mounted in bearings on the machine frame, an arm of a lever 120 clamped to the shaft 118 inside the machine frame, and a link 122 pivotally connected at one end to the lever 120 and slideable at its other end in a perforated block 124 rotatably mounted at the end of an arm extending from the elongated hub of the lever 109. Pivotally connected between the timing arm of lever 109 and a cam shifting arm 126 rotating on a stud 128 is a link 130. The upper end of the arm 126 pivotally supports an arcuate shoe 132 fitting a circular track in a sleeve 134 on the shaft 18, to which sleeve the awl stopping and starting cams 68, 70 are secured. The sleeve 134 is slotted axially at one end to receive tongue-like portions of a collar 136 pinned to the sewing shaft 18 by means of which the cams 68, 70 are caused to rotate with the shaft while permitting sliding movement thereon. When the treadle rod 114 is actuated, the connections thus described are shifted to bring either the stopping or starting cams selectively into alignment with their respective rolls, the timing arm roll 110 passing through the slotted portion of the disk 108 as the cams are shifted.

The treadle connections are also provided with yielding members. If the movement of the timing arm roll 110 is held up by a solid portion of the disk, a pair of springs 138 and 140 on link 122 is compressed temporarily until the slot in the disk registers with the stop roll. The springs 138 and 140 are secured between the perforated block 124 and a pair of clamps 142 on the link 122.

The treadle connections for the needle stopping and starting control cams 102, 104 are actuated at the same time as the awl stopping and starting connections. However, the active portions of the 70 needle control cams are displaced substantially 180° from the active portions of the awl control cams. The needle connections comprise a rod 144 pivoted at its upper end to a short arm on the lever 109 and at its lower end to one arm of a bell crank 146 (see Fig. 4) fulcrumed on a stud 148

secured to a bracket 150 on the machine frame. The bell crank 148 is in turn connected through a link 152 with a cam shifting arm 154 (see Figs. 3 and 12) fulcrumed on a stud 156 secured in the frame of the machine. The arm 154 supports at its free end an arcuate shoe 158 engaging a circular track in a sleeve 160 on the shaft 22, to one end of which sleeve the needle stop and start control cams 102, 104 are secured. The other end of the sleeve 160 is slotted to receive tongues extending from a collar 162 pinned to the sewing shaft 22 by means of which the cams 102, 104 are caused to rotate with the shaft while permitting sliding movement thereon.

The movements of the needle and awl starting and stopping control cams occur only when the slot in the timing disk 108 registers with the roll 110 on the timing arm of lever 109 and the disk is so located on the sewing shaft that the cams will be actuated in starting the machine only at a time just before the awl starting cam 70 is about to actuate its follower on the control arm 66. At this time, the needle starting cam is approximately 180° away from the roll on the needle control arm 92 so that the awl actuating mechanism will be connected almost immediately after the awl starting cam is actuated. Due to the timed relation between the needle and awl starting cams, the needle will not be connected until the sewing shaft has rotated substantially 180°.

Both the needle and awl actuating mechanisms are illustrated in Figs. 34 and 35 in stopped and locked positions at the ends of their strokes most remote from the work. After the timing lever roll 110 is moved through the slot in the disk 108 (Fig. 36), the awl control member disengages the locking arm 58 from the pin 48 and the awl actuating lever 38 is latched to the lever 40 to connect the awl to its actuating mechanism. The awl then starts its work penetrating stroke. During this time, the needle actuating mechanism remains disconnected, as illustrated in Fig. 37, until the needle controller member is shifted to the position of Fig. 31. After the awl has penetrated the work, the needle actuating lever 78 is latched to the driving lever 14 which by this time is brought into alignment with the needle actuating lever so that upon continued rotation of the sewing shaft, the needle will be set in motion.

The stopping cycle of the machine is similar to the starting cycle. With the needle and awl driving mechanisms connected to their respective mechanisms, as illustrated in Figs. 23 and 24, the treadle actuated connections are shifted when the slot in the timing disk 108 comes into alignment with the cam roll 110 so that the cam roll passes through the slot and the awl controller member shifts the slotted end of the locking arm 58 into engagement with the pin 48 to disconnect the awl driving and actuating levers while the awl bar is in stopping position at the upper end of its stroke, as illustrated in Fig. 25. During this time, the needle actuating mechanism remains connected, as shown in Fig. 26. The needle actuating mechanism is disconnected at the lower end of its stroke only after substantially 180° of rotation in the sewing shaft (see Fig. 31), the awl actuating lever remaining disconnected and locked at the uppermost end of its stroke, as indicated in Fig. 30. Thereafter, the sewing shaft is free to rotate and comes to rest as soon as its inertia becomes dissipated.

Rotation of the sewing shaft is controlled by a friction driving clutch constructed to provide slippage and easy variation of sewing speed, de-

pending upon the force applied to the treadle actuated connections. The arrangement is such that sufficient movement is imparted to the treadle actuated connections to cause the starting cams to be shifted into alignment with their cam rolls before the sewing shaft begins to rotate. If the slot in the timing cam is in proper position, this occurs simultaneously with the downward movement of the treadle rod 114, but if the timing arm of lever 109 is held from movement by the disk 108 at this time, the spring 146 in the treadle connections will be compressed until the sewing shaft begins to rotate. The timing arm will then complete its movement, causing the cams to be actuated in the manner stated.

Referring to Fig. 10, the driving clutch is of simple and conveniently accessible construction having a cone-shaped driving member 164 provided with a groove to receive a driving belt (not shown). The driving clutch member is rotatably mounted on a bearing 166 supported on the tubular portion of a cylindrical drum 168 slidably mounted in a close fitting circular recess surrounding the sewing shaft 18 at one end of the machine frame. To prevent displacement of the driving clutch member 164 along the tubular portion of the drum 168, the driving clutch member has a radial flange extending inwardly towards the tubular portion of the drum and the tubular portion has clamped to it outside the flange of the driving member a collar 170. The driven clutch member comprises a hand wheel 172 keyed to the sewing shaft 18 having an internal conical surface complementing the surface of the driving member 164. To hold the driving and driven members of the clutch separated, the cylindrical drum 168 is urged within the recess of the frame, as illustrated in Fig. 10, by a pair of compression springs 174 coiled around studs 176 passing loosely through openings in the machine frame at the sides of the sewing shaft and having their ends secured in the drum 168, the springs 174 being compressed between heads on the studs 176 and the machine frame.

To press the driving member 164 against the driven member 172 of the clutch, the shaft 118 has clamped to it a pair of arms 121, best shown in Fig. 4, engaging the heads of the studs 176 simultaneously when the treadle rod is depressed, pressing the studs and drum towards the right of Fig. 10 and bringing the friction surfaces of the clutch members together. One advantage of this construction is in the absence of any clutch actuating connections or clutch supporting bearing external of the machine frame in such a position as to interfere with removal or replacement of the driving belt on the grooved driving clutch member 164.

In clutches of machines of a similar nature heretofore constructed, a clutch actuating lever has been provided with one end disposed close to the exposed end of the sewing shaft or in contact with the outer surface of the driven clutch member so that in order to remove a driving belt on the driven clutch member, the lever must be disconnected or the ends of the belt separated. With the present construction, removal of the driving belt is greatly simplified since no obstruction is offered. Furthermore, the driving clutch member 164 is supported for rotation entirely by the sleeve on the cylindrical drum 168, no rotational force being transmitted, when the machine is stopped, to the sewing shaft 18 which has a separate bearing 175 in the machine frame. Also, oil within the frame 1 of the present machine is

kept from the clutching surfaces and all of the treadle connections inside the machine frame are protected against injury.

The presser foot 8 is secured to the lower end of a reciprocating presser foot bar 176 slidingly mounted in vertical bearings of the machine frame. The upper end of the bar has coiled about it a presser foot spring 178 compressed between a shoulder on the bar and a threaded bearing sleeve 180 surrounding the presser bar in the machine frame. The presser foot is raised briefly during each sewing cycle to permit the work to be fed, is lowered into work engaging position, and thereafter locked to prevent displacement of the work during the remainder of the sewing cycle by simple and effective mechanism connected with the awl bar 44. Connections are provided also for lifting the presser foot bar to disengage the presser foot from the work at the end of a seam operated from the awl control shaft 62.

The mechanism for actuating the presser foot during sewing comprises a sleeve 182 surrounding an enlarged portion of the presser foot bar 176. The sleeve 182 is slotted at one side to receive a double ended locking wedge 186, the ends of which are disposed in a wedge receiving groove 184 (see Fig. 6). The locking wedge 186 is fulcrumed for swinging movement on a bolt 188 passing through lugs on the sleeve 182 so that the ends of the wedge may move alternately into the groove in the presser foot bar. The enlarged portion of the presser foot bar on which the sleeve slides, in addition to the groove 184, has a lengthwise diametrical slot 190 so arranged that when either end of the locking wedge is forced into the groove, the halves of the bar defined by the slot will separate slightly to provide additional clamping and locking action against the inside of the sleeve 182.

To locate the sleeve 182 uniformly in a position lengthwise of the presser foot bar when the locking wedge 186 releases the bar, the sleeve is connected to one end of a tension spring 192 stretched between a pin on the sleeve and a pin on the presser foot bar. When the wedge unlocks the bar, the spring 192 draws the sleeve 182 yieldingly downwardly against the outer surface of the eccentric head on a bolt 194 passing loosely through a perforation in the machine frame and having an external check nut 196. By loosening the check nut 196, the eccentric head of the bolt 194 may be rotated to obtain suitable adjustment, the outer end of the bolt having a screw driver slot. The position of the sleeve is so adjusted that the mechanism for operating the locking wedge will also raise the presser foot a uniform amount (Fig. 5), will lower the presser foot while the upper end of the locking wedge is pressed into the groove of the presser foot bar, will release the presser foot momentarily as the presser foot reaches the surface of the work so that the presser foot may act yieldingly under the influence of spring 178, and thereafter the lower end of the wedge will again lock the presser foot in work engaging position (Fig. 6).

The connections of the presser foot actuating mechanism between the awl bar 44 and the locking wedge 186 include a roll 198 projecting from one side of the awl bar, a bell crank lever 200 fulcrumed on a bolt 202 secured in the frame of the machine and provided with a vertical arm having a cam slot 204 surrounding the roll 198 and a link 206 connecting the other arm of the bell crank lever 200 with an arm on the locking

wedge 186. The cam slot 204 is so shaped that when the awl bar 44 is at the highest end of its stroke, the bell crank lever 200 will have actuated the locking wedge and presser foot bar 176 upwardly. As the awl bar begins to descend from the position of Fig. 5, the roll 198 moves into an active portion of the slot 204, lowering the presser foot bar with the upper end of the wedge still locked in the groove of the presser foot bar until the sleeve 182 engages the eccentric head on the bolt 194 or the presser foot engages the work, whichever happens first. As soon as the sleeve 182 engages the eccentric head on the bolt 194 or the pressure foot engages the work, movement of the sleeve is arrested and the upper end of the locking wedge is withdrawn from the groove 184 during continued movement of the lever 200. This continued movement of the lever 200 causes the locking wedge to release the presser foot bar and permits the presser foot to engage the work under the force of spring 178. Thereafter, as the bell crank lever 200 completes its motion and until the straight dwell portion of the cam slot 204 is reached, the locking wedge swings still further in the same direction about the bolt 188, causing the lower end of the locking wedge to enter into locking relationship with the presser foot bar. Upward pressure exerted by the work on the presser foot while the lower end of the locking wedge is within the groove tends to lock the parts with increasing force so long as the bell crank lever 200 remains in position. The locked condition of the presser foot bar is retained by a straight portion of the slot 204 during the remainder of the awl penetrating stroke. During the retracting stroke of the awl, the lower end of the locking wedge is again withdrawn from the groove in the presser foot bar and the presser foot raised from engagement with the work after the upper end of the locking wedge is forced within the groove of the bar. This is the condition when the machine is stopped (Fig. 5).

For lifting the presser foot bar at the end of a sewing cycle to disengage the presser foot from the work, the forward end of the awl control shaft 62 has an arm 208 forming a toggle with a short link 210 connecting a lifting lever 212 rotatable on a fixed pivot 214. The left end of the lever 212 extends beneath a pin 216 on the presser foot bar, which pin also acts as a means of connection for the presser foot lock actuating spring 192. When the machine is running, the toggle comprising arm 208 and link 210 is broken, as indicated in Fig. 23, the link 210 having an elongated slot surrounding a pin 218 in one arm of the lever 212 to permit movement of the arm 208 after the toggle is broken without affecting the position of lever 212.

The awl stop cam 68 is shaped with a changing curvature so that after the cam has been moved along the sewing shaft into alignment with the roll on the awl stop arm 64, the locking lever 58 will disconnect and lock the awl actuating lever 40 at the upper end of its stroke, the link 210 sliding on the pin 218 without moving the presser foot lifting lever 212 (see Fig. 25). Accordingly, the work still remains clamped by the presser foot. Further rotation of the sewing shaft 18 brings a dwell portion of the stop cam 68 against the roll on the stop arm 64, as illustrated in Fig. 28. This dwell portion causes the control shaft 62 to remain stationary with the awl disconnected at the upper end of its stroke and the needle connected to its actuating mechanism until the needle has

entered and retracted from the work to complete the final stitch. The position of the needle actuating parts at this time is illustrated in Fig. 29. Thereafter (Fig. 30), a further change in curvature on the stop cam 68 causes the control shaft to rock still further to the position of Fig. 34, straightening the toggle 208, 210 and swinging the lifting lever 212 against the pin 216 to raise the presser foot from the work. During this operation, the needle actuating mechanism also is disconnected, as indicated in Fig. 31. Continued rotation of the sewing shaft causes no further movement to be imparted to the awl control shaft, the downward pressure of the presser foot on the lever 212 tending to lock the toggle lever 208 and link 210 in aligned positions.

As a means for holding the awl control shaft 82 in the position to which it is moved by the control cams, there is a pin 219 (see Figs. 5 and 8), mounted eccentrically of the control shaft on the hub of the stop arms 66 for connecting one end of a toggle spring 220 passing across the axis of the control shaft and having its other end anchored in an eye bolt 222 carried by the machine frame. The toggle spring 220 tends to hold the control shaft in either of two extreme positions with the ends of an open slot on the stop arm 66 against a limit pin 224 also carried in the frame of the machine.

Referring more particularly to Figs. 8 and 9, the thread tension wheel 14 is constructed from a sheet of relatively thin spring metal with radially disposed fingers bent into substantially parallel relationship with the axis about which the wheel rotates along their thread engaging portions and provided with radial prongs at the ends of the fingers for retaining the thread on the bent portions of the fingers. The fingers are so arranged that when the thread is wound in a complete circuit about the wheel, the fingers will yield slightly to sudden applications of tension on the thread. The cut-away portions of the wheel between the fingers also reduce undesirable effects of inertia in the wheel.

To resist rotation of the tension wheel 14, the wheel is secured to one end of a spool 226 fitting within semi-circular recesses of a bracket 228 on the machine frame and of a brake arm 230 pivoted at one end on a screw 232 in the bracket 228. Between the ends of the brake arm 230, there is a passage to receive a tension adjusting bolt 234 supported within an aligned opening of the bracket and surrounded by a spring 238 confined between the arm and a thumb nut 236. The other end of the brake arm 230 carries a set screw 240 engaged by a pin 242 slidably mounted in the machine frame and acted upon at its upper end by a lug on the awl control cam shifting arm 126. When the awl control cam shifting arm is operated to disconnect the awl from its actuating mechanism, the tension arm 230 is depressed, relieving the frictional force applied to the tension wheel supporting spool 226. Since this occurs before the final stitch of the seam is completed, the final stitch is not set with the same degree of tension as applied in previous stitches, so that the needle loop is drawn more freely through the work than in the previous stitches. As a result, the sides of the final loop, while retained on the needle, may readily be freed from the needle hook or one side of the loop severed with a longer length of thread available at the end of the seam to form a locking stitch when drawn through the loop of the previous stitch.

The looper 10, as in the machine of the Merrick patents, is in the form of a flat perforated carrier secured to the lower end of a looper arm 244. In the present machine, the looper arm is clamped at its upper end to a bar 246 slidably mounted in a rotatable guideway 248 carried in a vertical bearing at the under side of the overhanging arm on the machine frame. The rearward end of the bar 246 is provided with a hub surrounding a crank 250 on a vertical shaft 254 rotating in a fixed bearing, the shaft 254 being driven through bevel gears 256 and 258 from the sewing shaft 18. The upper end of the looper arm 244 is constructed with a horizontal finished surface bearing against a corresponding surface 260 on the under side of the machine frame and as the crank 250 is rotated, the looper arm 244 travels in a path around the surface 260, imparting to the thread guiding end of the looper 10 a corresponding movement about the needle path. During rotation of the crank 250, the guideway 248 swings slightly from side to side about its pivotal mounting, the thread being led to the looper over a pulley 262 on a downwardly extending portion of the guideway 248.

In the patented machine, the looper moves in a substantially circular path. In the illustrated machine, the looper mechanism above described actuates the looper in a path 263 which is elliptical with its greater axis extending in the direction of feed, as indicated in Fig. 21. This shape of looper path, as shown in dot-dash line 263, is an advantage where the needle feeds the work during the looping operation. Also, where a flat perforated looper is employed (see Fig. 22), the flat sides of which extend in the direction of feed, the looper may be adjusted to move closer to the needle at all times without danger of striking it.

To render the operation of the looper more effective in laying the thread in the hook of the needle and to reduce the tendency of the thread to impart sudden rotary movements to the tension wheel and so cause inaccuracies in stitch formation, a suitable combined pull-off and take-up acts simultaneously with the looper to maintain a more even tension on the thread and to compensate for the thread requirements of the looper during its looping operations.

On the lower end of the crank 250 is a continuously rotating take-up plate 264 having a rounded and polished periphery slidably engaging the thread at substantially right angles to its path as it passes between two guides 266 and 268 on its way from the thread tension wheel to the looper. These guides are secured in the tension wheel bracket 228 and the plate 264 acts to take up thread as the looper moves rearwardly by deflecting the thread from a straight path and to give up thread from between the guides as the thread is laid in the hook of the needle. Preferably, the take-up plate 264 is so shaped that a continuous withdrawal of thread is obtained from the tension wheel during a substantial portion of each sewing cycle with as little variation in rotary movement of the wheel as possible. In this way, the effects on thread tension caused by frequent starting and stopping the wheel in each sewing cycle are avoided.

In the machine of the Merrick patents, the needle is actuated while engaging the work to feed the work by one mechanism and to reinforce the needle, as well as to otherwise facilitate sewing and work feeding operations, the cast-off of that

machine is actuated to cover the barb of the needle by another mechanism separate and independent from the needle feeding mechanism. The cast-off 12 of the present machine is a reversely bent pointed arm illustrated most clearly in Figs. 11 and 15 to 20 inclusive, having a grooved upper end fitting the barbed side surface of the needle 2 and is actuated by the same mechanism employed to impart work feeding movements to the needle.

The needle bar 82 reciprocates in a carrier 270 formed at its lower end with a horizontal bore fitting a bar 272 and at its upper end with a rectangular lug loosely supported in a slot in the machine frame, which guide bar and slot act as guideway members for the carrier during feeding movements of the needle. The cast-off is supported on a bar 274 slidably mounted in suitable bearings of the carrier 270 in advance of the needle bar 82 with respect to the direction of feed and the cast-off is bent towards the needle partially surrounding it along the barbed side of its surface. By constructing and arranging the cast-off in this way, it is possible to cause the cast-off to follow the needle hook closely as the needle retracts from the work (Fig. 15) and to be retained to advantage in a position between the work and the hooked end of the needle while the needle is disengaged from the work.

To actuate the cast-off, the cast-off supporting bar 274 has pivoted to its lower end a roll 276 embraced by a slotted portion at one end of an angular link 278 forming a part of the needle carrier actuating mechanism. The other end of the angular link 278 is pivotally connected to an arm 280 attached to a rock shaft 282. The rock shaft 282 also has secured to it a bifurcated arm 284 surrounding a three-cornered feed cam 286 on the sewing shaft 22. At the angle of the link 278, there is a stud screw 288 on which is rotatably mounted a pair of blocks 290 and 292. The block 290 is slidably disposed between the flanges of a channeled guide arm 294 adjustably secured at an angle to the vertical in the frame of the machine and the block 292 slides between parallel downward extensions from the needle bar carrier 270. To secure the guide arm 294 in adjusted position, it has a rearwardly extending stud 296 journaled in the machine frame (see Figs. 12, 13 and 14), and a slotted clamping sector 298 is fixed to the stud outside the frame, a cap screw 300 passing through the slot in the sector and into the side of the frame to clamp the sector to the frame.

The feed cam 286 is shaped to cause the link 278 to be reciprocated vertically in the direction of needle reciprocation after the needle enters the work (Fig. 19), which movement causes the block 292 to slide in the channel of arm 294 to impart a horizontal work feeding component of movement, as illustrated in Fig. 20, to the upper end of link 278 as a result of the angle at which the arm 294 is set. The horizontal component of movement in the link 278 is transmitted to the needle carrier through the block 292 engaging the downward extensions from the carrier. The extent of feeding movement imparted to the needle carrier is readily adjustable by changing the angle of the channel arm 294 after having loosened the cap screw 300. In changing the extent of movement of the needle carrier, the vertical movement of the link 278 and therefore of the cast-off remains the same.

It is necessary for the cast-off to engage the work in a chainstitch sewing machine only as the

threaded hook of the needle is being withdrawn from the work. In the present machine, this occurs when the needle carrier has reached the end of its work feeding movement (see Figs. 15 and 17). The mechanism for actuating the needle towards and from the work is so timed with respect to the needle feeding mechanism that as the needle is disengaged from the work (Fig. 15), the back feeding movement is started.

10 As indicated in Figs. 16 and 18, when the needle has reached the lower end of its stroke, the upper pointed end of the cast-off is mid-way between the work and the hook of the needle so that the needle hook is free and unobstructed.

15 To sever the thread at the end of a seam, the machine is equipped with a thread cutter having an arcuate loop separating knife 302 (see Fig. 15), secured at the upper end of a vertical arm on a bell crank lever 304 fulcrumed on a screw 306 mounted in the machine frame. A horizontal arm of the lever 304 is connected through a long vertical link 308 to an arm 310 made fast to the control shaft 96 of the needle actuating mechanism, this shaft being rocked when the needle has reached substantially its lowermost position. When the control shaft 96 is rocked, the knife 302 swings across the needle path between the hook of the needle and the work, severing one side of the loop in a well-known manner.

20 30 One feature of the invention herein disclosed forms the subject-matter of a divisional application Serial No. 470,465, filed December 29, 1942, relating to improvements in driving clutches for sewing machines. Another feature, relating to a cast-off actuating mechanism, herein disclosed, forms the subject-matter of a divisional application Serial No. 444,355, filed May 25, 1942.

25 35 The nature and scope of the invention having been indicated, and a particular embodiment of the invention having been specifically described, what is claimed is:

30 40 1. A shoe sewing machine having, in combination, work penetrating instruments including a needle and an awl, a sewing shaft and connections for actuating the needle and awl alternately to enter the work, said connections comprising an element movable to disconnect one of said instruments from the sewing shaft, and means for moving said element during the final sewing cycle of a seam as the other of said instruments completes the sewing cycle.

45 50 2. A shoe sewing machine having, in combination, a needle, an awl, a sewing shaft and connections for actuating the needle and awl alternately to enter the work, said connections comprising an element movable to disconnect the awl from the sewing shaft, and means for moving said element during the final sewing cycle of a seam as the needle is completing the sewing cycle.

55 60 3. A shoe sewing machine having, in combination, a needle, an awl, a sewing shaft and connections for actuating the needle and awl alternately to enter the work, said connections comprising an element movable to disconnect the awl from the sewing shaft, sewing shaft driven

65 70 means for moving said element during the final sewing cycle of a seam to cause the awl to come to rest out of engagement with the work as the sewing shaft continues to rotate, and means for bringing the needle to rest out of engagement with the work while the awl remains stationary.

75 80 4. A shoe sewing machine having, in combination, a needle, an awl, a sewing shaft for actuating the needle and awl, separate trains of con-

nections connecting the sewing shaft with the needle and awl to cause the needle to enter the work when the awl withdraws comprising elements movable to disconnect the needle and awl from the shaft, and means for moving said elements at different times in the final sewing cycle of a seam to cause the needle to continue in motion and the awl to withdraw from the work and remain stationary until the final sewing cycle is completed.

5. A shoe sewing machine having, in combination, a needle, an awl, a sewing shaft for actuating the needle and awl, separate trains of connections connecting the sewing shaft with the needle and awl to cause the needle to enter the work when the awl withdraws comprising elements movable to disconnect the needle and awl from the shaft in a predetermined sequence, controller members driven from the sewing shaft to move said elements, and means for causing the controller members to act in the same sequence when the sewing operations are being started as when the sewing operations are being stopped.

6. A shoe sewing machine having, in combination, a needle, an awl, a sewing shaft for actuating the needle and awl, separate trains of connections connecting the sewing shaft with the needle and awl to cause the needle to enter the work when the awl withdraws comprising elements movable to disconnect the needle and awl from the shaft, controller members driven from the sewing shaft for moving the needle and awl disconnecting elements, and timing means for preventing actuation of the needle controller member except in a predetermined relationship with the time of actuation of the awl controller member when the sewing operations are being stopped.

7. A shoe sewing machine having, in combination, a needle, an awl, a sewing shaft for actuating the needle and awl, separate trains of connections connecting the sewing shaft with the needle and awl to cause the needle to enter the work when the awl withdraws comprising elements movable to disconnect the needle and awl from the shaft, controller members for the needle and awl connections driven from the sewing shaft, and a timing disk on the sewing shaft acting when sewing operations are being started or stopped to prevent actuation of the needle controller member before the awl controller member.

8. A sewing machine having, in combination, devices cooperating to perform sewing operations, a sewing shaft, separate trains of connections for actuating said devices in timed relationship from the sewing shaft comprising elements movable to disconnect the devices from the shaft, separate controller members actuated by the shaft in a predetermined sequence for moving said elements, and means for locking said devices in the positions to which they are moved when disconnected from the sewing shaft.

9. A sewing machine having, in combination, devices cooperating to perform sewing operations, a sewing shaft, separate trains of connections for actuating said devices in timed relationship from the sewing shaft comprising elements movable to disconnect the devices from the shaft, control cams driven by the sewing shaft for moving said elements to cause the devices to be connected or disconnected from the shaft in a predetermined sequence, treadle actuated means for causing the cams to actuate said elements, and timing means for preventing actuation of said

elements by the control cams except at a time in each sewing cycle when the formation of a new stitch is to be started.

10. A sewing machine having, in combination, devices cooperating to perform sewing operations, a sewing shaft, separate trains of connections for actuating said devices in timed relationship from the sewing shaft comprising elements movable to disconnect the devices from the shaft, and separate controller members actuated by the shaft in a predetermined sequence for moving said elements.

11. A sewing machine having, in combination, devices cooperating to perform sewing operations, a sewing shaft, separate trains of connections for actuating said devices in timed relationship from the sewing shaft comprising elements movable to disconnect the devices from the shaft, separate controller members actuated by the shaft in a predetermined sequence for moving said elements, means for locking said devices in the positions to which they are moved when disconnected from the sewing shaft, and means actuated from the main sewing shaft when the machine is being started for unlocking said devices one after the other in the same sequence in which the devices are disconnected from the sewing shaft.

12. A shoe sewing machine having, in combination, a needle operating from one side of the work, an awl operating from the other side of the work, a sewing shaft, crank driven mechanisms for actuating the needle and awl to follow each other closely during each sewing cycle, an element movable to disconnect the awl from the sewing shaft, and means for actuating said element to cause the awl to be brought to rest in a position out of engagement with the work before the needle completes its sewing cycle and withdraws from engagement with the work.

13. A shoe sewing machine having, in combination, a needle, an awl, a sewing shaft for actuating the needle and awl, separate trains of connections connecting the sewing shaft with the needle and awl to cause the needle to enter the work when the awl withdraws comprising elements movable to disconnect the needle and awl from the shaft, controller members for actuating the needle and awl disconnecting elements, control cams driven from the sewing shaft and movable relatively to the controller members towards and from positions of cooperation with said controller members to actuate said elements in predetermined sequence, and timing means for preventing relative movement of the control cams except when the sewing shaft is in a predetermined position.

14. A shoe sewing machine having, in combination, a needle, an awl, a sewing shaft for actuating the needle and awl, separate trains of connections connecting the sewing shaft with the needle and awl to cause the needle to enter the work when the awl withdraws comprising elements movable to disconnect the needle and awl from the shaft, controller members for actuating the needle and awl disconnecting elements, control cams driven from the sewing shaft and movable relatively to the controller members towards and from positions of cooperation with said controller members to actuate said elements in predetermined sequence, a slotted timing disk on the sewing shaft, an arm for moving the control cams relatively to the controller members, and a roll on the arm engaging with the timing disk to prevent relative movement of the cams

except when the slot in the disk is in line with the path of movement of the roll.

15. A shoe sewing machine having, in combination, a needle, an awl, a sewing shaft for actuating the needle and awl, separate trains of connections connecting the sewing shaft with the needle and awl comprising elements movable to disconnect the needle and awl from the shaft, a driving clutch for the shaft, treadle actuated means for causing the clutch to drive the shaft, means for actuating said elements while the shaft is rotating to disconnect the needle and awl including controller members and yielding connections for causing the treadle means to render the controller members operative, and timing means for preventing the treadle connections from rendering the controller members operative except when the sewing shaft has reached a predetermined point in its rotation.

16. A shoe sewing machine having, in combination, stitch forming devices, a sewing shaft, mechanisms for actuating the stitch forming devices comprising an element movable to disconnect at least one of said devices from the sewing shaft, a controller member for moving said element, means on the sewing shaft for operating the controller member, and a thread cutter connected with the controller member for severing the thread at the end of a seam.

17. A shoe sewing machine having, in combination, a needle, a sewing shaft, mechanisms for actuating the needle comprising an element movable to disconnect the needle from the sewing shaft, a controller member for moving said element, means on the sewing shaft for operating the controller member after the needle has withdrawn from the work, and a thread cutter connected to the controller member for severing the thread between the needle and the work at the end of a seam.

18. A shoe sewing machine having, in combination, a needle, a sewing shaft, mechanisms for actuating the needle comprising an element movable to disconnect the needle from the sewing shaft, a controller member for moving said element, a thread cutter for severing the thread between the needle and the work, and a control cam on the sewing shaft for actuating the controller member and cutter at the end of a seam.

19. A shoe sewing machine having, in combination, a needle, a sewing shaft, mechanisms for actuating the needle comprising an element movable to disconnect the needle from the sewing shaft, a controller member for moving said element, a thread cutter for severing the thread between the needle and the work, a control cam on the sewing shaft for actuating the controller member and cutter, and a treadle actuated member for causing the control cam to be shifted into operative position along the shaft relatively to the controller member at the end of a seam.

20. A shoe sewing machine having, in combination, a hook needle, a sewing shaft for actuating the needle, a looper for laying the sewing thread in the needle hook, crank mechanism driven from the sewing shaft for actuating the looper, and a take-up operated by said crank mechanism for taking up and giving up thread simultaneously with the movements of the looper.

21. A shoe sewing machine having, in combination, a hook needle, a sewing shaft for actuating the needle, a looper for laying the sewing thread in the needle hook, crank mechanism driven from the sewing shaft for actuating the looper, and a continuously rotating plate driven

from the sewing shaft having a thread engaging periphery disposed at right angles to the thread for taking up and giving up thread simultaneously with the movements of the looper.

5 22. A shoe sewing machine having, in combination, a hook needle, a sewing shaft for actuating the needle, a looper for laying the sewing thread in the needle hook, crank mechanism driven from the sewing shaft for actuating the looper, a sewing thread tension, and a take-up driven from the sewing shaft constructed and arranged to obtain a continuous withdrawal of thread from the tension during a substantial portion of each sewing cycle.

10 23. A shoe sewing machine having, in combination, a hook needle, a sewing shaft for actuating the needle, a looper for laying the sewing thread in the needle hook, crank mechanism driven from the sewing shaft for actuating the looper, a sewing thread tension, a rotating plate driven from the sewing shaft to cause continuous withdrawal of thread from the tension during a substantial portion of each sewing cycle, and means for guiding the thread at an angle to the 25 plate as it passes towards and from engagement with the plate.

20 24. A shoe sewing machine having, in combination, a hook needle, a sewing shaft for actuating the needle towards and from the work and 30 in the line of the seam to feed the work, a flat perforated looper, the flat sides of which extend in the direction of feed, for laying the sewing thread in the needle hook, and mechanism for actuating the looper in an elliptical path the greater axis of which extends in the direction of feed.

35 25. A shoe sewing machine having, in combination, a needle, a sewing shaft for actuating the needle, a friction controlled tension wheel, 40 an element movable to disconnect the needle from the sewing shaft, a controller member for moving said element, a treadle operated member for rendering the controller member operative or inoperative, and connections actuated by the 45 treadle member for releasing the friction on the tension wheel before the needle is disconnected.

26. A shoe sewing machine having, in combination, stitch forming devices, a work support and a presser foot for holding the work adjacent the point of operation of the stitch forming devices, a reciprocating bar to which the presser foot is secured, and presser foot actuating means including a spring for urging the presser foot 55 yieldingly towards the work, presser foot lifting and lowering mechanism, a sleeve on the presser foot bar, and a locking wedge on the sleeve connected to the lifting mechanism for gripping the presser foot bar when the lifting mechanism is moved in either direction.

60 27. A shoe sewing machine having, in combination, stitch forming devices, a work support and a presser foot for holding the work adjacent the point of operation of the stitch forming devices, a reciprocating bar to which the presser foot is secured, and presser foot actuating means including a spring for urging the presser foot 65 yieldingly towards the work, presser foot lifting and lowering mechanism, a sleeve on the presser foot bar, a locking wedge on the sleeve connected to the lifting mechanism for gripping the presser foot bar when the lifting mechanism is moved in either direction, a stop for holding the sleeve in a position where the locking dog is free of the presser foot bar when the lifting mechanism is 70 inoperative, and means for holding the sleeve 75

yieldingly against the stop to cause the presser foot bar to be released momentarily as the lowering movement of the lifting mechanism takes place.

28. A shoe sewing machine having, in combination, stitch forming devices, a work support and a presser foot for holding the work adjacent the point of operation of the stitch forming devices, a reciprocating presser foot bar having a lengthwise diametrical slot, and presser foot actuating means including a presser foot lifting mechanism, a sleeve on the presser foot bar and a locking wedge on the sleeve connected to the lifting mechanism for separating the halves of the bar defined by the slot to provide clamping action of the bar against the sleeve.

29. A shoe sewing machine having, in combination, work penetrating instruments including a needle and an awl, a sewing shaft and connections for actuating the needle and awl alternately to enter the work, said connections comprising an element movable to disconnect one of said instruments from the sewing shaft when said instrument reaches a predetermined stopping position, a work support, a presser foot acting with the work support to hold the work adjacent the point of operation of stitch forming devices, a reciprocating bar to which said one instrument is connected, and actuating connections between the reciprocating bar and the presser foot comprising a cam roll on the bar, a lever having a cam arm with which the roll cooperates shaped to raise the presser foot from the work when said one instrument is in stopping position.

30. A shoe sewing machine having, in combination, a needle, an awl, a sewing shaft and connections for actuating the needle and awl alternately to enter the work, said connections comprising an element movable to disconnect the awl from the sewing shaft when the awl reaches a predetermined stopping position, a work support, a presser foot acting with the work support to hold the work adjacent the point of operation of the awl, a reciprocating awl bar, and connections acting during sewing operations between the awl bar and the presser foot comprising a cam roll on the awl bar, and a lever having a cam arm with which the roll cooperates shaped to raise the presser foot from the work during each sewing cycle as the awl reaches stopping position.

31. A shoe sewing machine having, in combination, a needle, an awl, a sewing shaft and connections for actuating the needle and awl alternately to enter the work, said connections comprising an element movable to disconnect the awl from the sewing shaft when the awl reaches a predetermined stopping position, a work support, a presser foot acting with the work support to hold the work adjacent the point of operation of the awl, a reciprocating awl bar, connections acting during sewing operations between the awl bar and the presser foot comprising a cam roll on the awl bar, and a lever having a cam arm with which the roll cooperates shaped to raise the presser foot from the work during each sewing cycle as the awl reaches stopping position, and a controller member actuated by the sewing shaft at the end of a seam to move said element and simultaneously to raise the presser foot beyond the point to which it is raised by the sewing connections.

32. A shoe sewing machine having, in combination, work penetrating instruments including a needle and an awl, a main sewing shaft for actuating the needle and awl, a work support and presser foot for clamping the work operated upon, separate trains of connections between the sewing shaft and the needle and awl comprising an element movable to disconnect one of said work penetrating instruments from the sewing shaft, a control cam on the sewing shaft for moving said element, treadle actuated means for shifting the cam to cause said one instrument to be connected or disconnected, and connections actuated by the control cam for raising the presser foot from engagement with the work when the element is moved to disconnect said instrument.

33. A shoe sewing machine having, in combination, work penetrating instruments including a needle and an awl, a main sewing shaft for actuating the needle and awl, a work support and presser foot for clamping the work operated upon, separate trains of connections between the sewing shaft and the needle and awl comprising an element movable to disconnect one of said work penetrating instruments from the sewing shaft, a starting control cam for moving said element to connect said instrument, a stopping control cam for moving said element to disconnect said instrument, treadle actuated means for shifting the cams selectively to connect or disconnect said one instrument, and connections operated by the stopping cam for raising the presser foot from engagement with the work after said instrument is disconnected.

34. A shoe sewing machine having, in combination, work penetrating instruments including a needle and an awl, a main sewing shaft for actuating the needle and awl, a work support and presser foot for clamping the work operated upon, separate trains of connections between the sewing shaft and the needle and awl comprising an element movable to disconnect one of said work penetrating instruments from the sewing shaft, a stopping control cam having a portion of changing curvature for moving said element to disconnect said instrument while the sewing shaft is rotating and a second portion of changing curvature for raising the presser foot from engagement with the work after said instrument is disconnected, and treadle actuated means for causing the cam to be rendered operative or inoperative.

35. A shoe sewing machine having, in combination, a needle, an awl, a sewing shaft for actuating the needle and awl, separate trains of connections connecting the sewing shaft with the needle and awl to cause the needle to enter the work when the awl withdraws comprising elements movable to disconnect the needle and awl from the shaft, a stopping control cam for moving the needle element to disconnect the needle from the sewing shaft, another stopping control cam having two portions of changing curvature, one of which moves the awl element before the needle is disconnected to disconnect the awl from the sewing shaft and another of which raises the presser foot from engagement with the work after the needle is disengaged from the work, and treadle actuated means for causing the cams to be rendered operative or inoperative.

BERNARD T. LEVEQUE.
